UNITED STATES PATENT OFFICE.

FRANCIS BRUCKER, OF SHELBY, OHIO, ASSIGNOR TO THE STANDARD MANUFACTURING COMPANY, OF SHELBY, OHIO.

SPRING-HINGE.

No. 918,502.

Specification of Letters Patent.

Patented April 20, 1909.

Application filed August 15, 1907. Serial No. 388,658.

To all whom it may concern:

Be it known that I, FRANCIS BRUCKER, citizen of the United States, residing at Shelby, Ohio, have invented certain new and 5 useful Improvements in Spring-Hinges, of which the following is a specification.

My invention relates to double acting spring hinges for doors, of that class in which a post or stem acts, as the door is 10 turned, upon a plunger and against a spring, the reaction of which tends to return the door to its normal or closed position.

My invention consists in improved details of construction, in this form of spring hinge, 15 the nature and purpose of which are herein-after fully set forth, and illustrated in the accompanying drawings, in which—

Figure 1 is an elevation of a portion of a door and its frame, disclosing the hinged 20 construction embodying my invention as applied thereto. Fig. 2 is a horizontal sectional plan of the hinge construction before its application to the door. Fig. 3 is a side elevation of the same, the inclosing shell or 25 cover being removed in both Figs. 2 and 3. Fig. 4 is a plan view of the floor plate. Fig. 5 is a transverse section on line 5—5 of Fig. 3. Figs. 6 and 7 are respectively a vertical longitudinal section and a plan of the inclos- 30 ing shell or casing. Fig. 8 is a section on line 8—8 of Fig. 3 looking toward the right, and Fig. 9 is a detail plan view showing the manner of connecting or fastening the rear 35 end of the shell or casing. Fig. 10 is a view of a modification.

This hinge is composed of two parts, one to be attached to the door, and the other to the sill or floor. As shown the working parts are held in a frame A, composed of 40 two steel strips 5 and 6, the bent ends of which 5^a and 6^a, are connected to their opposite parts as illustrated at 6^b. The part 5, projected at 5^a, is perforated for screws whereby it is attached. The other part has 45 a detachable screw 14, for like purpose, this screw being preferably held in part 6 by reverse thread. The spring 11 located in this frame, is held at one end on a nut 10 having holes 10^a for turning and threaded on stem 50 7, fixed in part 6^c of frame. The other end of this spring bears on shoulders 8^a of the shank 8 of the plunger. This plunger shank is inclosed in the coil and has a head 9 with two arms 9^b, which embrace the post at 55 e (Fig. 5) and bear on studs f which are

fixed to a disk d formed with or fixed to the post, so that, (the post being held fast) the swinging of the frame A with the door, in either direction, will cause a stud to press the shoulders of the plunger against the 60 spring, and reaction of the spring on the stud will tend to return the door. The head and arms rest on this disk d, and are supported thereby, and above them is another annular disk 4, with interior edge 4^a up- 65 turned, closely fitting the reduced upper end of the post. Axial therewith and over disk 4 is an inverted cup, 6^a, fixed to the upper frame part at 6^a, the downward flange of which incloses the upward flange of disk 4 70 at such distance as to leave an annular way for the anti-friction rollers shown in Fig. 5.

It will be understood that the post, in the form shown, rests in the floor piece or a fixed piece independent of the frame, and 75 the frame and door rest on the post turning on these rollers, the post, in this action, being held rigidly. The post also passes through the lower frame part 5, and its foot, preferably slightly tapered is stepped with the floor 80 piece as shown at a, Fig. 5. While this post is normally held rigidly in the floor piece, it is capable of slight rotary movement therein and also in relation to the frame and door for purpose of adjustment and alinement of the door. To this end the post bearings in the frame are round as is the post bearing hole in the plate 2^a which is provided with a slot 2^b leading into said hole, in which lies a horizontal stem 12, fixed in 85 the foot of the post and extending horizontally between adjusting screws 13 (Figs. 4 and 5) in the floor piece. By adjusting these screws the post may be slightly turned in relation to the floor piece and frame and 90 door, so that the studs f may be made to so bear on the plunger arms, that when the door is at rest and closed it will aline accurately, and this may be done readily and without removal of any part. This floor 95 piece is shown in Figs. 3, 4 and 5.

The door edge being properly recessed the frame is applied by turning in the wood screw 14 (the thread of its wood end being reversed to the metal thread end in the frame) using the frame as a handle until it is home, when the free end 5^a is sprung up into its mortise and secured by screws.

In order to provide an ornamental appearance for the frame without expensive 110

nickel plating of the frame or other expensive surfacing, and at the same time to render it easily covered and accessible, I have provided a shell of sheet metal shown in Figs. 6 and 7. As shown it is in a single piece shaped to snugly inclose the frame with plain sides 16^a, enlarged at the rear ends as shown at 16^b and with top flanges 17. At the rear end is a screw hole for connection with the frame, and at the front the side walls are turned in and provided with a slot 7^a which engages with ears 18^a on a cross plate 18, fixed to the ends of the frame. The shell may be pushed on from the rear the ends engaged with the ears, and held by the screw 19. Or it may be made in two halves interlocking on the rear as shown in Fig. 10.

It will be observed that the head of the plunger is held snugly between disks 4 and 4 and thus the shank is sustained in parallel relation with the frame and spring. Its free end also extends therefrom unconfined except by the spring. This construction is free from rattling in operation, a matter of no small importance.

I claim in combination substantially as described:

1. A door hinge frame with means for attachment, a post in said frame, disks on said post, studs between the disks, an armed plunger having its head located between the disks and its arms bearing on the studs and having also a stem and a spring encircling the stem.

2. A door hinge comprising a frame, a post thereon, a disk fixed on said post, studs mounted on said disk, a spring actuated plunger provided with arms adapted to bear on said studs, an upper disk seated on said studs and having an inner upturned flange encircling the upper end of said post, an

inverted cup secured to the frame and inclosing the upper flange of said upper disk and forming therewith an annular ball race-way and anti-friction balls in said way. 45

3. In a door hinge, a frame, a post seated in a floor plate and provided with separated disks, a plunger whose head is sustained between said disks and operates on the post, 50 a spring encircling the shank of said plunger and an adjusting nut on the frame at the other end of the spring.

4. In a spring hinge, a frame for carrying the operating parts, an inclosing shell 55 embracing the sides of the frame, an interlocking connection between the extremities of said sides and the frame for locking said sides to the frame, and a screw for securing said shell to the frame at the butt of the 60 hinge.

5. In a spring door hinge, a frame containing the spring and coöperating parts, and adapted for attachment to the door and an inclosing shell comprising side members 65 having slotted ends adapted to be engaged by tongues carried at one end of the frame, and means for securing said shell parts in place at the opposite end of the frame. 40

6. In a door hinge, a frame, a post therein, disks on said posts having horizontal parallel portions, and studs between said disks, a spring actuated plunger having a head confined between the parallel portions of said disks, said head having arms bearing 75 on the studs, and means whereby the angular relation of the studs with relation to the frame may be varied.

In testimony whereof, I affix my signature in presence of two witnesses.

FRANCIS BRUCKER.
